UNITED STATES PATENT OFFICE.

JOHN S. HOLLIDAY, OF WILKINSBURG, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY SIGNALING.

1,127,438.

Specification of Letters Patent.

Patented Feb. 9, 1915.

Application filed July 26, 1913. Serial No. 781,286.

To all whom it may concern:

Be it known that I, JOHN S. HOLLIDAY, a citizen of the United States, residing at Wilkinsburg, in the county of Allegheny and State of Pennsylvania, have invented 5 certain new and useful Improvements in Railway Signaling, of which the following is a specification.

My invention relates to track circuit 10 apparatus for railway signaling, and particularly to apparatus for alternating current track circuits.

I will describe two forms of apparatus embodying my invention, and will then 15 point out the novel features thereof in claims.

In the accompanying drawings, Figure 1 is a diagrammatic view showing a section of track of a direct current electric railway 20 provided with one form of track circuit apparatus embodying my invention, both track rails of the railway being included in the circuit of the propulsion current. Fig. 2 is a diagrammatic view showing a section of 25 track of an alternating current electric railway provided with another form of track circuit apparatus embodying my invention, Fig. 3 is a view showing in front elevation a device B shown in Fig. 1. Fig. 3^A is a 30 sectional view on the line III—III of Fig. 3 looking in the direction indicated by the arrows. Fig. 4 is a view showing in front elevation a device B' shown in Fig. 2. Fig. 4^A is a sectional view on the line IV—IV of 35 Fig. 4 looking in the direction indicated by the arrows. Fig. 5 is a diagrammatic view showing a section of track of an electric railway provided with track circuit apparatus embodying my invention, only one track 40 rail being included in the circuit of the propulsion current. Fig. 6 is a diagrammatic view showing a section of track of a steam railway provided with track circuit apparatus embodying my invention.

Similar reference characters refer to similar parts in each of the views.

Referring first to Fig. 1, the numerals 1, 2 designate the track rails of a railway, a section A of which is electrically separated 50 from the rails of the adjoining sections by insulated joints 3. The railway here shown is an electric railway the propulsion current for which is supplied from a direct current generator C, one terminal of which is

connected with a trolley wire or third rail 55 6 and the other terminal of which is connected with the track rails 1 and 2 through a differential bond 5. In order that both of the track rails 1 and 2 may be included in the circuit of the propulsion current, I 60 provide inductive bonds 4 adjacent the insulated joints 3 to conduct the propulsion current around these joints in a usual and well known manner.

The track section A is provided with a 65 track circuit comprising the track rails 1 and 2 of the section, a source of alternating signaling current, and a track relay. As here shown, the source of signaling current is a transformer T whose secondary is connected with the track rails and whose primary is connected with transmission mains 7 to which alternating signaling current is supplied by a generator G. The track relay, which is designated R, is as here shown 70 a polyphase type of relay comprising a rotor 18 and two stator windings 19 and 20. Winding 20 is connected with the track rails, and winding 19 is connected with a secondary 8 of a transformer T' whose primary is connected with the transmission mains 7. The rotor 18 operates a contact 21 which is included in a local circuit 10 which controls a signal S governing traffic through block section A. The local circuit 10 for 85 signal S is supplied with energy by another secondary 9 of transformer T'.

With only the apparatus thus far mentioned, it will be seen that when a car or train occupies the track rails at or near the 90 point at which the secondary of transformer T is connected with the rails, the wheels and axles of the car or train would short-circuit this secondary so that a heavy current would be drawn therefrom. In order to limit the 95 current which is drawn at such times from the transformer T, and yet not impose an undesirable impedance in the track circuit, I interpose in the connection between the transformer secondary and one track rail 100 a device B which I will now describe.

Referring to Figs. 3 and 3^A, the device B as here shown comprises a magnetizable field 11, formed of a plurality of laminations of transformer iron clamped together 105 by rivets 15. This field is provided with a winding 12, which, as shown in Fig. 1, is included in the connection between the sec-

ondary of transformer T and track rail 2. The field 11 is substantially U-shaped; located between the poles formed by the legs of the field is a rotor member 13 formed of a plurality of laminations of transformer iron clamped together between two end plates 30^a and 30^b of electro-conductive material such as copper. This member 13 is mounted on an arbor 14 which is supported in suitable bearings which are not shown. Member 13 is provided with a closed circuit of electro-conductive material comprising the two copper end plates and two bars 16 passing through the member and electrically connected with both end plates. These bars 16 serve also to clamp the end plates and laminations together. The movement of member 13 is limited to oscillation through a small arc of a circle by two stationary stops 22, 22^a between which moves a tongue 17 projecting from a collar 24 fixed on the arbor 14. Member 13 is biased to the position shown, that is, to such position that tongue 17 engages stop 22^a, by a counterweight 23 comprising a screw 23^a fitting into a threaded boss on collar 24 and a nut 23^b adjustable on the screw. Referring to Figs. 1 and 3, the operation of the device B is as follows: When the member 13 is in the position shown, a certain amount of alternating magnetic flux produced by current in the winding 12 passes through the closed circuit formed by the bars 16 and the end plates. This alternating flux causes current to flow in this circuit, and the effect of this current is to produce torque tending to turn member 13 in clockwise direction as viewed in Fig. 3, against the action of counterweight 23. The device is so proportioned that at the maximum current drawn from the transformer T when section A is unoccupied, the torque on member 13 is not sufficient to move this member against the action of counterweight 23. When, however, a car or train occupies the rails of section A it reduces the impedance in the circuit of the secondary of transformer T and the current in this circuit therefore increases. This increased current in winding 12 produces sufficient flux to move member 13 against the action of the counterweight, so that tongue 17 moves toward stop 22. When member 13 is in this position, the plane of the closed circuit carried thereby is more nearly parallel with the direction of the flux passing between the poles of field 11 than before, so that a smaller proportion of the total flux passes through this closed circuit and a larger portion will pass through the member 13 outside of the closed circuit. The impedance of the entire device measured across the terminals of winding 12 is then increased, for the reason that a greater amount of flux flows in the magnetic circuit in proportion

to the current in winding 12. Although the current drawn from the transformer T with member 13 in this position is greater than when the track rails are unoccupied, still the power taken from the transformer is actually less than when the rails are unoccupied; the reason being that when the impedance of the device is increased, the angle of lag of the current behind the voltage is increased so that the power, which is the product of the voltage, current and cosine of angle of lag, is less than the power when the rails are unoccupied. 70 75

It will be seen that direct current in winding 12 has no tendency to produce torque on member 13, because a constant magnetic flux in member 13 will not produce current in the closed circuit which includes bars 16; hence, the presence of direct propulsion current in winding 12 has no effect on the device B other than to magnetize the field core 11. 80 85

Referring now to Fig. 2, the apparatus shown therein is similar to that shown in Fig. 1, except that in Fig. 2 the propulsion generator C' is an alternating current generator. The propulsion current and the signaling current differ in frequency, the frequency of the former usually being 25 cycles and that of the latter 60 cycles. B' is a device which, like the device B in Fig. 1, is placed between the transformer T and the track to limit the power drawn from the transformer when the track is occupied. This device B' is operated by current of the signaling frequency, but not by current of the propulsion frequency. 90 95 100

Referring to Figs. 4 and 4^A, the device B' comprises a magnetizable field 11^a formed of a plurality of laminations of transformer iron clamped together by rivets 15. This field, as here shown, is E-shaped, having three projecting legs 25, 25^a, and 25^b. The middle leg 25 is provided with a winding 12 which, as shown in Fig. 2, is included in the connection between the transformer secondary and one track rail 2. Mounted between the two outside legs 25^a and 25^b is a member 13^a which is similar to the member 13 shown in Fig. 3 and hereinbefore described. The end of leg 25 is also in close proximity to member 13^a as shown. It will be seen that there are two paths for the magnetic flux produced by current in winding 12, viz., through leg 25^a, and through leg 25^b. Both of these paths include a part of the member 13^a. The bars 16 are so located that when member 13^a is in the position shown, the same proportion of the flux in each of the two paths will flow through the closed circuit which includes bars 16 and the end plates. Hence, if the fluxes in these two paths are equal, the amounts of flux in the closed circuit formed by plates 30^a and 30^b, and bars 16 are also equal. That part of 110 115 120 130

this flux which passes through leg 25^a will set up a torque tending to turn the rotor counter clockwise, so that a plane through bars 16 will be cut by a minimum of flux. 5 Similarly a clockwise torque will be set up by the flux entering leg 25^b. If the fluxes in the two paths are equal, the resultant torque is zero. Means are provided for causing the flux produced by 25 cycle current in winding 12 to be equal in the two paths, but for causing the flux produced by 10 60 cycle current to predominate in the path including leg 25^b. As here shown, this means consists in making the air gap 27 between leg 25^b and member 13^a greater than 15 air gap 27^a between leg 25^a and member 13^a, and in providing a band 26 of electro-conductive material encircling leg 25^a. The band 26 forms a short-circuited secondary 20 and acts in the well known manner to decrease the magneto-motive force tending to produce flux along the path including leg 25^a. The band 26 and the difference between the lengths of air gaps 27 and 27^a, are so 25 proportioned that with 25 cycle current in winding 12 the fluxes in the two magnetic paths are balanced, but that with 60 cycle current in winding 12 the flux in the path including leg 25^b is greater than that in the 30 path including leg 25^a. Hence, any propulsion current which may flow in winding 12 has no tendency to produce torque on member 13^a.

Referring to Figs. 2 and 4, the operation 35 of the device B' is as follows: When the member 13^a is in the position shown in Fig. 4, a certain amount of flux produced by the signaling current in the winding 12 passes through the closed circuit formed by the 40 bars 16 and the end plates. This flux causes current to flow in this circuit and the effect of this current is to produce torque tending to turn member 13 in clockwise direction as viewed in Fig. 4 against the action 45 of counterweight 23. The device is so proportioned that at the maximum current drawn from transformer T, when section A is unoccupied, the torque on member 13^a is not sufficient to move this member against 50 the action of counterweight 23. When, however, a car or train occupies the rails of section A, it reduces the impedance in the circuit of the secondary of transformer T, and the current in this circuit therefore 55 increases. This increased signaling current in winding 12 produces sufficient flux to move member 13^a against the action of the counterweight so that tongue 17 then moves toward stop 22. When the member 13^a is 60 in this position, the plane of the closed circuit carried thereby is more nearly parallel with the direction of the flux passing through the magnetic circuit including leg 25^b, so that a smaller proportion of the total 65 flux in this path passes through this closed

circuit and a larger proportion passes through the member 13^a outside of the closed circuit. The impedance of the entire device measured across the terminals of winding 12 is then increased. Although the current drawn from the transformer T with member 13^a in this position is greater than when the track rails are unoccupied, still, the power taken from the transformer T is actually less than when the rails are unoccupied; the reason being the same as hereinbefore explained in describing device B shown in Figs. 1 and 3.

Referring now to Fig. 5, I have here shown a section of track of a direct current electric railway, one rail only of the two track rails being included in the circuit of the propulsion current. Rail 2 is electrically continuous, and rail 1 is divided by insulations 3 to form block sections. One terminal of the generator C is in this case connected directly with the continuous rail 2. In a railway of this type there is generally a difference of potential of the direct propulsion current between the two track rails 1 90 and 2, but as pointed out hereinbefore the device B is not responsive to this current. The operation of the apparatus shown in Fig. 5 will be apparent from the foregoing explanation of the operation of the apparatus shown in Fig. 1.

In Fig. 6 I have shown a section of track of a steam road, both track rails being divided by insulations 3. The apparatus shown in this view is similar to that shown 100 in Fig. 1, and the operation will be apparent from the foregoing explanation of Fig. 1.

Although I have herein shown and described only two forms of track circuit apparatus embodying my invention, it is understood that various changes and modifications may be made therein within the scope of the appended claims without departing from the spirit and scope of my invention.

Having thus described my invention, what I claim is:

1. An impedance device comprising a winding, and a movable member comprising a closed circuit of electro-conductive material located in the path of the magnetic flux produced by current in said winding, the movement of the member being between two positions in which different proportions of the flux pass through the closed circuit.

2. An impedance device comprising a magnetizable field having three projecting legs, a winding on the middle leg, a movable member comprising a closed circuit of electro-conductive material located in both paths of magnetic flux from the middle leg to each of the other legs, the air gaps between said member and the two outside legs being of unequal reluctance, and a closed circuit of electro-con-

- ductive material surrounding the outside leg which is separated from said movable member by the air gap of least reluctance.
3. An impedance device comprising a 5 winding, a magnetizable core for said winding having two paths in multiple for the flux produced by current in said winding, a movable member having a closed circuit of electro-conductive material interposed in 10 both of said paths, the air gaps between said member and the core being unequal in the two paths, and a closed circuit of electro-conductive material surrounding the path having the lesser air gap.
- 15 4. An impedance device comprising a winding, a magnetizable field core having two paths in multiple for the flux produced by current in said winding, a movable member having a closed circuit of electro-conductive material located in both of said 20 paths, and means for balancing the fluxes in said closed circuit from said two paths when alternating current of one frequency flows in said winding and for unbalancing the 25 fluxes in said closed circuit from said two paths when alternating current of another frequency flows in said winding.
5. An impedance device comprising a magnetizable field, a winding for said field, 30 and a magnetizable member carrying a closed circuit of electro-conductive material mounted in the path of the magnetic flux flowing in said field, said member being movable between two positions in which 35 different proportions of the flux pass through the closed circuit.
6. An impedance device adapted to be used in an electric circuit in which alternating current of one value flows at one time 40 and alternating current of another value flows at another time, said device comprising a winding, adapted to be energized from the circuit carrying alternating current, and a member comprising a closed circuit of electro-conductive material located in the path 45 of the flux produced by current in said winding, said member being movable between two positions in which different proportions of the flux pass through said closed circuit, 50 and said member being biased to the position in which the greater proportion of flux passes through said closed circuit, said device being so adjusted that when the alter-

nating current of lesser value flows in said winding the torque exerted on said member 55 is not sufficient to move the member in opposition to its bias, but that when the alternating current of greater value flows in said winding the torque exerted on said member is sufficient to move the member to the position in which the lesser proportion of flux passes through said closed circuit whereby the impedance offered by said device to the alternating current flowing in its winding is then increased.

7. An impedance device adapted to be used in connection with an electric circuit carrying alternating currents of two frequencies a and b , current of frequency b having one value at one time and another 70 value at another time, said device comprising a winding adapted to be energized from the circuit carrying alternating currents, a magnetizable field having two paths in multiple for the flux produced by currents in 75 said winding, a member having a closed circuit of electro-conductive material located in both of said paths, means for balancing the fluxes produced in said two paths by alternating current of frequency a and for unbalancing the fluxes produced in said two paths by alternating current of frequency b , said member being movable between two 80 positions in which different proportions of the flux produced by the alternating current 85 of frequency b pass through said closed circuit, and said member being biased to the position in which the greater proportion of said flux of frequency b in one path passes through said closed circuit, the device being 90 so adjusted that the torque exerted on said member by the lesser value of alternating current of frequency b is not sufficient to move the member in opposition to its bias but that the torque exerted by the greater 95 value of current of frequency b is sufficient to move the member to the position in which the lesser proportion of the flux produced by alternating current of frequency b passes through said closed circuit.

In testimony whereof I affix my signature in presence of two witnesses.

JOHN S. HOLLIDAY.
